Primary Examiner — Jennifer L Watkins(74) *Attorney, Agent, or Firm* — Laubscher & Fretwell, PC(57) **CLAIM**

The ornamental design for a bag, as shown and described.

DESCRIPTION

FIG. 1 is a front perspective view of a bag according to my invention;

FIG. 2 is a side perspective view thereof;

FIG. 3 is a top perspective view thereof;

FIG. 4 is a rear elevation view thereof;

FIG. 5 is a front elevation view of the bag of FIG. 1 in an open condition; and,

FIGS. 6-8 are front elevation views, respectively, of the bag of FIG. 1 in successive folded conditions.

The broken lines depict stitching and form no part of the claim.

1 Claim, 4 Drawing Sheets(56)
